THOMAS M. HUSTIN, OF ORANGE, INDIANA.

Letters Patent No. 94,890, dated September 14, 1869.

IMPROVEMENT IN MACHINE FOR FILING SAWS.

The Schedule referred to in these Letters Patent and making part of the same.

To all whom it may concern:

Be it known that I, THOMAS M. HUSTIN, of Orange, in the county of Fayette, and in the State of Indiana, have invented certain new and useful Improvements in Machines for Filing Saws; and do hereby declare that the following is a full, clear, and exact description thereof, reference being had to the accompanying drawings, and to the letters of reference marked thereon, making a part of this specification.

The nature of my invention consists in the construction of a machine for filing saws, and in the arrangement of the devices hereafter set forth and explained.

Figure 1 is a side elevation of my machine.

Figure 2 is an end view of the same.

Figure 3 is an end view of file-holder.

Letter A represents the frame or bed upon which my machine rests, and which may be of any desired shape or size.

Secured to an upright standard, at one end of the frame, is the eccentric B, to which is attached the arm C, for drawing the file back and forth, so as to sharpen the saw.

Upon the opposite end of the shaft to which the eccentric is secured, is the small cog-wheel D, which gears with, and communicates motion to the wheel E.

Just under the eccentric B, is the cam-wheel F, which is secured to the same shaft as the wheel E.

Upon the periphery of this wheel, there are three or more cams, which operate the lever G, and which has an indentation cut in its surface, in which the lever H catches, so as to move the frame, to which the saw is fastened forward for a new cut of the file.

Secured in a semicircular bed, on top of the frame, is the disk I, to which the frame for holding the saw, while being filed, is secured.

As this disk is only held down in place, it allows the frame K to be freely turned in any direction.

Moving back and forth in this frame, is the slide L, upon the top of which are placed the saw-clamps M, for holding the saw.

The upper part of this slide is loose, so that it can be moved independently of the other part, by means of the rod N, which extends from one end to the other.

By turning one of the thumb-screws, at the ends of this rod, which has a screw-thread cut on its surface, at the point where it passes through the arm O, the saw can be moved to any desired point, without the trouble of moving the whole slide.

Extending up from the side of the frame, are the brace P and spring R, which clasp the saw just at the point where it is being filed, in order to prevent it from bending or shaking.

Suspended from an arm, projecting out from the disk I, is a slotted lever, S, which has a hooked dog on its end, (as shown in red lines in fig. 2,) which

catches in the toothed bar T, on the under side of the slide, so as to move it forward, at each revolution of the cam-wheel F, for the file to cut in the next tooth.

Placed just back of this lever, is the screw U, which regulates the distance which the slide is to be moved.

Attached to a cross-piece, which binds the frame K together, is a spring, V, which draws the lever S back to its position after it has moved the slide forward.

The end of the lever H is fastened to the bottom of the slotted lever S, by means of a pin; and, as the cam-wheel F turns, moving it upward and sideways, it forces the dog on the end of the lever to catch in the rack-bar T.

To the opposite end of the lever G from the cam-wheel, is attached the upright screw-rod U, which supports the file at any desired height. As the cams on the wheel strike the end of the lever, it raises this rod upward, carrying the file with it, raising it from the saw, while it is being moved forward.

In order to regulate the pressure of the file on the saw, a spring, X, has been attached to the end of the lever, which can be varied at pleasure, by changing the length of the connecting-pin.

Upon the rod W, is placed a block, Y, which supports one end of the file-holder. In this block, is placed a burr or nut, by means of which the file can be lowered or raised to any desired point.

The end of the file-holder passes through a slot cut in the block, and out through the one in the upright Z, which serves as a guide to it while moving back and forward.

Extending up from the frame A, is the support b, which has a curved slot cut in it, so that the guide c, which holds the heel of the file, can be raised or lowered at will.

This heel d consists of a block, in which the rear end of the file is secured, and has a number of vertical grooves, extending upward on its end, as seen in fig. 3.

In the front end of the block e, there are corresponding grooves made, so that the heel d will fit in them, and move up and down, so as to give elasticity to the file.

The file-bar f, which connects the two parts of the file-holder together, is secured to the top of the heel d, and passes back over the end of the block e.

About the middle of this block, the screw g, having a spiral spring around its surface, is passed through the bar into the block, securing them together, but at the same time allowing the file-bar to play up and down, so as to let the file adjust itself to the saw.

Through the back end of this bar, is the screw i, the lower end of which bears upon the arm C, so as to regulate the height at which the file is to be raised while moving back and forth.

To the back end of the block k, which holds the

front end of the file, is the segment *n*, which is pivoted on, in such a manner as to be turned freely around, so as to change the file from the edge to the flat side. In the top of this segment, there are a number of holes made, through which a pin is passed, so as to secure it at any desired point.

In each of the blocks *d* and *k*, which hold the file, there is placed a small round cylinder, *o*, in which there is made a triangular opening, (as shown by red lines in fig. 3,) in which the end of the file is placed, and then is secured by means of a screw, or any suitable device. The one in the heel *d* is movable, and can be turned entirely around, but the one in the block *k* is secured firmly to the segment *n*, and forms an axle, on which it turns.

In order to accommodate the holder to files of every length, the block *k* is made to slide back and forth on the bar *f*, and is secured at any desired point by means of a screw, *l*.

In using this machine, there is but one shaped file that will answer the purpose perfectly, and this is a three-cornered one, of the same size from end to end, without any taper at any point.

Having thus described my invention,

What I claim, and desire to secure by Letters Patent, is—

1. The block *Y*, provided with a burr, so that the file can be lowered or raised, and working on the screw-rod *W*, in combination with the file-bar *f*, screw *g*, and set-screw *i*, constructed to operate as and for the purposes set forth.

2. The slide *L*, moving back and forth in the frame

K, and provided with the clamps *M*, brace *P*, and spring, and so constructed that it can be moved by means of the screw-rod *N*, so as to adjust the saw without loosening the clamps, substantially as shown.

3. Providing the heel of the file with grooves, so that it can move up and down, for the purpose of giving elasticity to the file, substantially as set forth.

4. The set-screw *i*, bearing upon the arm *C*, so as to raise the file upward in its backward motion, in combination with the screw *g*, having a spiral spring around its surface, arranged to operate for the purpose described.

5. The cylinder *o*, in which the ends of the file are secured, in combination with the segment *n*, when used substantially as specified.

6. The segment *n*, having openings in its top, so that it can be secured at any desired point, for giving a suitable pitch to the file, substantially as described.

7. Levers *H* and *S*, spring *V*, and cam-wheel *F*, when used to move the slide forward, in combination with the screw *U* and slide *L*, when constructed as described, and operated by the screw-rod *N*, substantially as shown.

8. The file-holder, when composed of the file-bar *f*, grooved wheel *d*, block *k*, segment *n*, and cylinders *o*, when combined substantially as described.

In testimony that I claim the foregoing, I have hereunto set my hand, this 20th day of April, 1869.

THOMAS M. HUSTIN.
